MACHINE FOR RAMMING UP MOLDS AND THE LIKE

Shelley M. Stoody and Ralph L. Abos, Whittier, Calif., assignors to Stoody Company, Whittier, Calif., a corporation of California

Application July 20, 1942, Serial No. 451,540

3 Claims. (Cl. 22—46)

This invention relates to a method and means for ramming up molds and the like which molds are useful for casting purposes.

There are numerous instances where a multiplicity of molds must be rammed up about identical patterns to enable casting of a multiplicity of identical articles. The present invention contemplates a method and a machine which will enable such molds to be easily, quickly, and uniformly rammed up.

In ramming up molds it is highly desirable and usually quite important that the molding sand or molding composition be rammed up or packed in a flask about a pattern with a high degree of uniformity for if the molding material is loosely rammed in one portion of the mold and tightly packed or compacted in another portion of the mold the castings obtained are apt to be non-uniform and faulty. This is particularly true where the casting is formed of a relatively high melting point metal alloy and where precision castings are required.

A primary object of the present invention is to therefore provide a means and apparatus for ramming up molding material in a flask about a pattern in such a manner that a high degree of uniformity can be obtained.

In general, the present method and apparatus contemplate introducing molding material into a flask in a succession of small quantities, applying pressure to each quantity after it has been introduced, and while the pressure is being applied, imparting a plurality or series of sharp blows or impacts to the material. We have found that if the molding material is introduced into the flask about the pattern and straight or simple pressure is applied thereto without impact that the molding material tends to stratify under the pressure so that there are striations or seams through it. These usually are most noticeable under the area or areas of application of pressure. The portions of the mold that are not directly beneath the area or areas of application of pressure are apt to remain loose. However, if pressure is applied to the molding material fed into the flask and a plurality of impacts or percussive blows are applied by the pressure-applying means to the molding material while the pressure is being applied, we find that the formation of striations or seams in the molding material is largely, if not, entirely, eliminated. Furthermore, the impacts tend to distribute the compression created by the pressure applied throughout the molding material so that it is uniformly compacted not only beneath the area

or areas that apply the pressure but elsewhere throughout the mold. Consequently, if the pressure-applying means does not accurately fit the interior of the flask or closely fit about the pattern, the molding material is nevertheless firmly compacted throughout the interior of the flask and closely around the surfaces of the pattern.

Another object of the invention is to provide a machine for ramming up molding materials around patterns in flasks wherein molding material is successively fed in small quantities into the flask and rammed up in the above-described manner before the introduction of a succeeding quantity of molding material is introduced and to provide a pressure-operated means for moving a ramming hammer into and out of the flask. In this manner as the flask is gradually filled by the addition of consecutively introduced amounts of molding material the pressure with which the ramming hammer is forced against the molding material is maintained uniform regardless of the height of the molding material in the flask. In other words, the pressure applied by the ramming hammer will remain the same when the flask is substantially filled as when the filling of the flask has just started.

A further object of the invention is to provide a conveniently arranged means for varying the length of time that the ramming hammer applies pressure to the molding material in the flask and consequently the number of percussive blows imparted thereby during each cycle of operation of the machine. Thus some molding materials possess such characteristics that they need only be lightly rammed up in the flask to secure the desired castings. Other molding materials have such characteristics that they must be heavily rammed up in the flask and rendered quite compact and dense. By means of the adjustment which the present invention affords, the machine can be quickly adjusted to take care of the requirements of the molding materials which may vary considerably.

Still another object of the invention is to provide a molding machine having a novel, simple, and highly advantageous means for mounting a flask thereon, and also a means for holding a pattern therein in desired position.

With the foregoing and other objects in view, which will be made manifest in the following detailed description and specifically pointed out in the appended claims, reference is had to the accompanying drawings for an illustrative embodiment of the invention, wherein:

Figure 1 is a front view in elevation of the

molding machine embodying the present invention serving to illustrate the preferred form of apparatus that may be used for performing the method of the present invention;

Fig. 2 is a partial view in front elevation, parts being broken away and shown in vertical section, illustrating the flask-holding means and illustrating the ramming hammer as having been introduced into the flask;

Fig. 3 is a view in side elevation of the molding machine illustrated in Fig. 1;

Fig. 4 is a view in vertical section illustrating the upper portion of the pneumatic hammer that forms a part of the present machine and illustrating the control mechanism of the machine;

Fig. 5 is an enlarged view in front elevation of the upper portion of the machine illustrating it in that position wherein the ramming hammer is being withdrawn from the flask;

Fig. 6 is a view similar to Fig. 5 illustrating the machine in that position wherein the ramming hammer is being forced downwardly into the flask;

Fig. 7 is a sectional view taken substantially upon the line 7—7 upon Fig. 5 in the direction indicated;

Fig. 8 is a horizontal section taken substantially upon the line 8—8 upon Fig. 7 in the direction indicated;

Fig. 9 is a vertical section taken substantially upon the line 9—9 upon Fig. 1 in the direction indicated; and

Fig. 10 is a horizontal section taken substantially upon the line 10—10 upon Fig. 9.

Referring to the accompanying drawings wherein similar reference characters designate similar parts throughout, the machine comprises a frame supported on a suitable base 10 and preferably consisting of a pair of upright columns 11 and 12 braced by suitable bracing indicated at 13. The columns 11 and 12 support upper and lower body plates 14 and 15 on which there are bearings or guides 16 for vertically reciprocable rails or slide bars 17 and 18 that are spaced forwardly of the columns 11 and 12.

The flask that it is desired to ram up with molding composition or molding sand is indicated at 19, and while this flask may assume different sizes and shapes depending upon the nature of the casting that it is desired to produce the flask illustrated is in the form of a short, hollow, carbon cylinder open at both top and bottom.

The pattern of the casting that is to be produced is illustrated at 20. This pattern will likewise assume various sizes and shapes depending upon the nature of the casting that is to be produced. If possible, however, it is highly desirable that the pattern be equipped at its upper end with one or more extensions 21 receivable in grooves 22 formed in the interior walls of the flask 19 so as to support and maintain the body of the pattern centrally of or in proper position with relation to the flask. We find it desirable also to have the bottom of the pattern equipped with an extension 23 that normally will project downwardly below the bottom of the flask. This extension is to be engaged by a holding means when the flask and pattern are positioned on the machine so that the bottom of the pattern will likewise be held either centrally of and in proper position within the flask.

On the lower body plate or frame plate 15 there is a flask support preferably consisting of two superposed plates 24 and 25. The upper plate 25 may have its upper surface recessed to form

a seat for the bottom of the flask 19, see Fig. 2. The lower plate is preferably apertured to receive the extension 23. The upper plate has secured to its underside adjacent the forward end thereof a small plate 26 that constitutes a stationary jaw engageable at its rear end with the forward side of extension 23. The movable jaw is indicated at 27 and is slidably mounted in the underside of plate 25. This jaw is adapted to be forced forwardly by a pneumatically operated diaphragm 28 housed within a housing 29 and supplied with compressed air or the equivalent through a supply pipe 30. A spring 31 enclosed within the housing urges the diaphragm into jaw-retracting position whenever pressure in supply pipe 30 is released. When pressure is applied to the diaphragm 28 through supply pipe 30 the movable jaw 27 is forced forwardly, see Fig. 10, and cooperates with the stationary jaw 26 to clamp on extension 23, thus firmly holding the bottom of the pattern in proper position with relation to the flask 19. On release of the pressure, spring 31 retracts the movable jaw 27 so as to disengage the extension 23 and enable the flask and the contained pattern to be removed.

The supply pipe 30 is supplied with compressed air or the equivalent from any suitable source and is controlled by a three-way valve 32, see Fig. 1, preferably located at any convenient location near the front of the machine. This three-way valve on manipulation will connect the interior of housing 29 with either the source of compressed air to close the movable jaw 27 or to the atmosphere to allow the movable jaw 27 to be opened under the action of spring 31.

As a means for clamping the flask 19 on its support afforded by the plates 24 and 25 a cross-head 33 is provided preferably recessed on its underside to receive the top of the flask, see Fig. 9. This crosshead is adapted to be pulled downwardly by a pair of pull rods 34 which are slidably mounted in guides 35, see Fig. 9, mounted on the back of a cross bar 36 that connects the lower bearings or slides 16 for the rails 17 and 18. Springs 37 surround the pull rods above the cross bar 36 and are adapted to be compressed when the crosshead 33 is pulled downwardly. They urge the crosshead into uppermost or flask releasing position whenever the lower ends of the pull rods are free to be moved upwardly thereby. The lower ends of the pull rods 34 are connected to a crosshead 38 which, in turn, is connected by a link 39 to a crank 40 on a rockshaft 41 suitably mounted on bearings secured to the lower frame plate 15. The rockshaft 41 is operable by a hand lever 42 so that when the hand lever 42 is forced downwardly crosshead 38 will pull crosshead 33 downwardly into clamping engagement with the flask compressing the compression springs 37. As a means for locking the crosshead 38 and consequently the crosshead 33 in flask clamping position and also tightening the crosshead 33 against the top of the flask with considerable mechanical advantage the crosshead 38 is equipped with a detent 43 engageable with a shoulder forming one side of a notch 44 in the rear side of a hold-down bar 45 which is pivotally suspended from between ears 46 on the underside of the plate 24. A rockshaft 47 extends through the ears and is operable by a handle 48. This rockshaft however has an eccentric portion 49 that extends through the upper end of a hold-down bar 45.

The arrangement is such that the hold-down bar 45 will normally swing by gravity in a rearward

direction against the detent 43. Consequently, when lever 42 is pressed downwardly the detent 43 engages the rear edge of the hold-down bar and ultimately enters the notch 44. The handle 48 can then be swung into the position shown in Fig. 9 which, because of the eccentric portion 49 on the rockshaft 47 forces the hold-down bar 45 downwardly a short additional distance with great mechanical advantage, thus causing the crosshead 33 to clamp upon the top of the flask with considerable pressure. The hold-down bar 45 serves to hold the crosshead 33 in this clamping position even though lever 42 is released.

When it is desired to release the flask 19 the handle 48 is swung upwardly and forwardly or in a clockwise direction from the phantom line position shown in Fig. 9 which causes the eccentric on the rockshaft 47 to release the high tension on the tension rods 34. The rockshaft also carries a small arm 50 having a lateral extension that extends behind the hold-down bar 45 so that when the handle 48 nearly completes its upward and forward swinging movement this extension engages the back of the hold-down bar and disengages it from the detent 43. The compressed springs 37 then become effective to lift the crossheads 33 and 38 and the tension rods 34 into their uppermost positions clearing the top of the flask 19 to enable its being removed.

Three crossheads 51, 52, and 53 connect the rails or slides 17 and 18 so as to be vertically reciprocable therewith. The upper crosshead 51 provides a mount for a pneumatic hammer which may be of any preferred or conventional construction. This hammer, generally designated at 54, is supplied with compressed air through a flexible tube or hose 55. It is provided with a control or trigger 56 that delivers the compressed air to the operating mechanism of the hammer which produces a short vertical reciprocation of its hammer 57. The second crosshead 52 serves to support a hopper 58 into which the molding material or molding sand 59 is placed. It also provides a brace portion 60 that clamps about the lower portion of the pneumatic hammer to hold it in position. The lower crosshead 53 provides a suitable bearing within which is vertically reciprocable a hollow ramming hammer 61. This ramming hammer is slidably mounted in the crosshead 53 and has vertical grooves or keyways 62 formed therein into which partially project balls 63 to form an anti-friction splined connection between the ramming hammer 61 and the crosshead whereby the ramming hammer may be vertically reciprocated but will be held against rotation relatively thereto. The ramming hammer 61 is separate from the hammer 57 of the pneumatic hammer 54. It is connected thereto however by a rubber shield 64 preferably in the form of an accordion pleat at cross-section which enables relative movement to take place between the hammer 57 and the ramming hammer 61 if occasion requires, but prevents the molding material 59 from entering between the hammers. As indicated on Fig. 9 the ramming hammer is hollow except at its upper end where it is engageable by the hammer 57. It is equipped with one or more ports 65 adjacent its upper end through which the molding material 59 may pass. A cup 66 is threadedly mounted or is otherwise rigidly secured on the ramming hammer 61 and telescopes over the spout at the lower end of the hopper. A compression spring 67 is compressed between the crosshead 53 and the

cup 66 and serves to continually urge the ramming hammer into its uppermost position.

As indicated on Fig. 9, sides of the bottom of the ramming hammer are recessed as at 68 to accommodate the extensions 21 at the top of the pattern when the ramming hammer is in its lowermost position within the flask 19. The ramming hammer thus provides areas 69 at its lower end adapted to engage and impact with the molding material 59 that is fed from the hopper 58 through ports 65 downwardly through the hollow ramming hammer.

The weight of the rails or slides 17 and 18, the crossheads thereon, the hopper 58 and its contents, and the pneumatic hammer, is largely counterbalanced by counterbalance levers 70 pivotally mounted on each side of the frame. The forward ends of these levers are connected by links 71 to the upper crosshead 51. Counterweights 72 are adjustably mounted on the rear ends of the levers.

The means employed for vertically reciprocating the carriage that comprises the rails 17 and 18, the crossheads 51, 52, and 53 and the structure mounted thereon is a pneumatic ram comprising a cylinder 73 mounted on the upper frame plate 14. Within this cylinder there is a double-acting piston 74 the rod of which, 75, extends through a stuffing box 76 and is connected as at 77 to the upper crosshead 51. When compressed air is delivered to the cylinder 73 on top of the piston 74 the piston is forced downwardly thus forcing the carriage downwardly and introducing the lower end of the ramming hammer into the flask. Conversely, when compressed air is delivered to the cylinder 73 below piston 74 the piston 74 and the carriage are elevated. On the forward side of the cylinder there is mounted a holder 78 on which is mounted a slide 79 for a vertically reciprocable cam 80. This cam is held onto the slide by means of cap screws or the equivalent indicated at 81 which extend through slots 82 therein. The side edges of this cam are engageable with the heads 83 of valve stems 84 of valves 85, 86, 87, and 88. Compressed air is supplied to the valves 85 and 88 through a supply pipe or conduit 89.

In the position shown in Fig. 5, the carriage is being elevated as indicated by the arrow at the bottom of this figure. The line of flow of compressed air is from the supply pipe 89 through valve 88 which has been opened by the cam 80 through a control or throttle valve 90 and through tubing 91 to the bottom of the cylinder 73. Air in the top of the cylinder is allowed to exhaust therefrom through tubing 92 through valve 86 which has also been opened by the cam 80 to the outlet 93 where it may discharge into the atmosphere. In this position it will be noted that valves 85 and 87 controlling flow to and from the top and bottom of the cylinder 73, respectively, are allowed to close by the cam 80.

In the position shown in Fig. 6, the carriage is descending as indicated by the arrow at the bottom of this figure. In this position the line of flow from supply pipe 89 is through the valve 85 past a throttle or control valve 94 and thence through tubing 95 to the top of the cylinder 73. The compressed air, however, has a divided path. Part of the air entering tubing 95 and passing to the top of the cylinder and the balance flowing past a throttle or control valve 96 through tubing 97 to a timing cylinder 98, the exhaust from which is controlled by a control valve 99.

before passing into the atmosphere. In this position it will be noted that the cam 80 has opened valve 81 permitting air in the bottom of cylinder 13 to be exhausted through tubing 100 to the exhaust outlet 93. It will also be noted that in this position valves 86 and 83 have been allowed to close by the valve member. 5

A lever 101 is pivoted as at 102 to the holder 18 and has a pin and slot connection 103 with the cam 80. A tension spring 104 connects the swinging end of this lever with an adjustable support 105. This spring and support are so arranged that the spring functions as a snap-over spring. Thus, if the cam 80 is moved into the position shown in Fig. 5, tension of the spring 104 is such as to cause the lever to tend to retain the cam member in this position until forcibly moved therefrom. Conversely, if the cam member has been moved into the position shown in Fig. 6, the tension of the spring 104 will tend to retain the cam 80 in this position until forcibly moved therefrom. The cam can be shifted into the position shown in Fig. 6 by means of a push rod 106 that is mounted for vertical reciprocation relative to the upper crosshead 51 by means of a bracket 107. This push rod which is vertically slidable in the bracket can be elevated relatively to the crosshead 51 by means of a lever 108 that is pivoted on the bracket as at 109 and which is connected to the push rod by means of a link 110. The lever has a handle 111 by which it may be swung into the dotted line position shown in Fig. 4, or into the full position shown therein. The lever has a nose 112 thereon which is engageable with the trigger 56 of the pneumatic hammer when the lever is swung into the dotted line position as indicated in Fig. 4. In this position it will be noted that a heel 113 engages the crosshead 51 in such a position that the pivotal connection 114 between the link 110 and the lever 108 is slightly beyond the center line joining the pivotal connection 115. Consequently, when the lever is shifted into the dotted line position shown in Fig. 4, the trigger of the pneumatic hammer will be retained in depressed position and the push rod 106 will be elevated into its uppermost position wherein it is engageable with the bottom of the cam 80. Consequently, when the carriage rises to the top of its stroke the push rod 106 will engage the cam 80 and shift it from the position shown in Fig. 5 to the position shown in Fig. 6, reversing the positions of the valves from the positions shown in Fig. 5 to the positions shown in Fig. 6 and causing air to be admitted to the top of the cylinder 13 to force piston 74 downwardly therein. 50

The means for shifting the cam 80 from the position shown in Fig. 6 into the position shown in Fig. 5 consists of the piston that is operable within the regulating cylinder 98. This piston, indicated at 116, see Fig. 7, has a rod 117 extending down through the bottom of the cylinder so as to be engageable with the top of the cam 80. It is urged into uppermost position by means of a spring 118. Air beneath the piston and within the cylinder may escape therefrom through a bleeding port 119 which is of predetermined size. 60

When the machine is in the position shown in Fig. 6, a portion of the air delivered through valve 85 passes to the top of the cylinder 13, as previously explained, and the balance thereof passes through tubing 97 into the top of the control cylinder 98. The rate at which this air may build up a pressure on top of piston 116 depends upon the extent to which control valve 99 is 70

opened. Thus, if valve 99 is opened rather widely most of the air delivered through tubing 97 may escape therewith with the result that considerable time is required to build up an air pressure on top of piston 116 to depress it against the action of spring 118. Conversely, if valve 99 is nearly closed the pressure within the cylinder 98 on top of piston 116 will build up quite rapidly with the result that the piston will be depressed against the action of spring 118 in a relatively short time. Whenever the piston is depressed the lower end of its rod 117 engages the top of cam 80 and shifts it from the position shown in Fig. 6 into the position shown in Fig. 5. Whenever the cam 80 is shifted from the position shown in Fig. 6 into the position shown in Fig. 5, the carriage, pneumatic hammer, ramming hammer, and associated structure are lifted from within the flask. Thus, by opening or closing valve 99 the length of time that the lower end of the ramming hammer remains in the flask can be varied. If valve 99 is nearly closed the ramming hammer will remain in the flask only a short period of time before sufficient pressure builds up in cylinder 98 to actuate piston 116 and effect a shift of cam 80. On the other hand, if valve 99 is opened rather widely, considerable time must elapse before the required pressure can build up to cause piston 116 to shift cam 80 and bring about a withdrawal of the ramming hammer from the flask. Thus, the length of time that the ramming hammer remains in the flask can be varied. 30

The operation of the above-described machine is as follows: Assuming that the flask 19 with its pattern 20 disposed therein is positioned on the flask support afforded by the plate 25 and has been clamped in position thereon by operation of the lever 42 and the handle 48, the machine is started in operation by swinging handle 111 from the full line position shown in Fig. 4 to the dotted-line position. This projects push rod 106 upwardly and as the carriage is initially at the top of its stroke, the upward movement of the push rod shifts the cam 80 into the position shown in Fig. 6. At the same time the trigger 56 of the pneumatic hammer is depressed so that the pneumatic hammer has its hammer continuously striking and reciprocating the ramming hammer 61. The movement of the ramming hammer 61 brings about a simultaneous short reciprocation or vibration of the cup 66 which tends to feed the molding material 59 through the port 65 down through the ramming hammer 61 and into the flask while the carriage and structure mounted thereon is descending. The molding material 59 is thus fed into the bottom of the flask about the pattern while the carriage is descending. When the lower end of the ramming hammer 61 encounters this material it is subjected to the pressure exerted by the pressure of the compressed air admitted to the top of cylinder 13 on top of piston 74. This pressure is maintained while usually two or more percussive blows are transmitted to the ramming hammer 61 by the pneumatic hammer. In the course of a relatively short time depending upon the extent to which valve 99 is opened the carriage is elevated, and during this upward movement the pneumatic hammer continues to operate transmitting downward blows to the ramming hammer 61. These blows however are mere idle blows inasmuch as the ramming hammer is ascending. When the carriage reaches the top of its stroke push rod 106 engages cam 80, shifts 65

the direction of flow of compressed air into the cylinder 73 and bringing about a descent of the carriage thus completing one complete cycle of operation. Each cycle of operation will, of course, cause a small additional quantity of molding material to be rammed up in the bottom of the flask about the pattern. However, regardless of the elevation to which the mold material has risen within the flask it will be noted that the pressure exerted thereon by the ramming hammer 61 independently of the percussive blows is constant, this being purely dependent upon the pressure of the compressed air applied to the top of piston 74 which is assumed to be obtained from a source of compressed air under constant pressure. The magnitude of the percussive blows transmitted to the ramming hammer 61 likewise is constant. Operation of the machine is continued until the flask has been completely rammed up after which the machine can be turned off by swinging handle 111 into the full-line position shown in Fig. 4. This releases trigger 56 shutting off the pneumatic hammer and allows push rod 105 to descend so that when the carriage reaches the top of its stroke the upper end of push rod 105 will not engage cam 60 and cause the succeeding descent of the carriage. Thus, on turning off the machine by handle 111 the carriage will rise to the top of its stroke and remain there until handle 111 is returned to the dotted line position shown in Fig. 4. With the machine shut off the movable jaw 27 can be caused to disengage the bottom of the pattern by manipulation of the three-way valve 32 and on releasing the crosshead 33 from engagement with the top of the flask, the flask can be removed.

In the construction illustrated the flask is a one-piece flask which has the pattern supported therein and the mold material rammed up about it. In making up a mold of this character we prefer to employ a pattern that is diecast of tin or equivalent metal having a relatively low melting point. When the mold is completed it may then be baked and when the mold is cured it can be heated to a sufficiently high temperature to melt out the pattern after which the mold is ready to have the casting metal poured therein. The extension 23 and the extensions 21 may form gates or risers for the mold cavity if the contents of the flask is removed therefrom either prior to or after baking.

It will be appreciated from the foregoing description that the present apparatus does not de-

pend upon the mere application of pressure alone to the molding material in the flask. If pressure alone is relied upon the molding material tends to stratify and to have striations developed or formed therein. By having a combined pressure and a sharp percussive rapping take place, a uniform ramming up of the mold is possible despite the fact that the lower end of the ramming hammer does not fit the entire flask closely nor does it fit closely about the pattern. By means of this method and apparatus we have been able to ram up molds rapidly, efficiently, and secure a high degree of uniformity enabling the casting of high melting point alloys and developing highly uniform precision castings.

Various changes may be made in the details of construction without departing from the spirit or scope of the invention as defined by the appended claims.

We claim:

1. A molding machine comprising flask supporting means, impact means for imparting a series of sharp blows to molding material introduced into a flask positioned on the flask supporting means, and pressure operated means for forcing the impact means into the flask with uniform pressure regardless of the extent to which it may be introduced into the flask and withdrawing it therefrom, and means for varying the length of time that the impact means is allowed to apply pressure and impacts to the molding material in the flask.
2. A molding machine comprising flask supporting means, a pneumatic hammer adapted to be moved into and to be withdrawn from a flask positioned on the flask supporting means, fluid pressure operated means for moving the pneumatic hammer into and out of the flask, and means for varying the length of time that the pneumatic hammer remains in the flask before being withdrawn therefrom.
3. A molding machine comprising flask supporting means adapted to have a flask supported thereon, a pneumatically operated hammer, means movably supporting the pneumatically operated hammer for movement into and out of the flask, a fluid pressure operated piston for reciprocating said means, and a time control means for varying the length of time that the hammer remains in the flask.

SHELLEY M. STOODY.
RALPH L. ABOS.
